UNITED STATES PATENT OFFICE.

JOHN D. SCHMIDT, OF NEW YORK, N. Y.

DESIGN FOR A PUZZLE-BOX.

SPECIFICATION forming part of Design No. 26,165, dated October 6, 1896.

Application filed August 1, 1896. Serial No. 601,391. Term of patent 3½ years.

To all whom it may concern:

Be it known that I, JOHN D. SCHMIDT, a citizen of the United States, residing at New York, in the county of New York and State of New York, have invented and produced a new and original Design for Puzzle Boxes or Cases, of which the following is a specification, reference being had to the accompanying drawings, forming a part thereof, in which—

10 Figure 1 is a plan view of my improved puzzle box or case, and Fig. 2 a section thereof on the line 2 2, these two views being deemed necessary to fully illustrate my design.

The leading feature of my new and original 15 design for puzzle boxes or cases consists of the circular bottom 5, upon the upper surface of which is secured in any desired manner four concentric vertical circular walls or flanges 6, 7, 8, and 9. The second circular 20 vertical wall or flange 7 is provided at its opposite sides with flanges or openings 10, the third vertical wall or flange 8 with four similar passages or openings 10, which are arranged at equal distance apart, and the central vertical wall or flange is provided at its 25 opposite sides with two similar passages or openings 10, which are in line with those formed in the second vertical flange or wall 7, and not in line with either of those formed 30 in the third vertical wall or flange 8. It will

also be observed that annular spaces 11 of the same width in cross-section are formed between the vertical walls or flanges 6, 7, 8, and 9, and that the central circular space within the central vertical wall or flange 9 is 35 divided by a transverse or diametrical flange or wall 12 into two semicircular chambers 13. There is also a narrow flange or space 14 between the outer central vertical wall or flange 6 and the perimeter of the bottom 15, and it 40 will thus be seen that the entire design is symmetrical in form, the lines thereof being all circular in form, with the exception of the central diametrical partition flange or wall 12, and that the circular lines are all arranged 45 concentrical.

Having fully described my new and original design, I claim as new and desire to secure by Letters Patent—

The design for a puzzle box or case herein 50 shown and described.

In testimony that I claim the foregoing as my invention I have signed my name, in presence of the subscribing witnesses, this 30th day of July, 1896.

JOHN D. SCHMIDT.
